[57] ABSTRACT

A key vise structure is disclosed wherein first and second vises are mounted on opposite ends of the frame and a movable vise jaw in each vise is moved by an end of a beam spring. The central portion of the beam spring is moved toward the vise jaws by means of a mechanical advantage means, shown in the preferred embodiment as a manual handle and a toggle mechanism. This simultaneously clamps both vises closed upon keys for use in a key machine. The key vise structure is also provided with a shoulder gauge for the key with a spring acting to yieldably urge the shoulder gauge into each of a gauging and a retracted position and this shoulder gauge is retracted by linkage means as the vises are moved to the clamped position. The foregoing abstract is merely a resume of one general application, is not a complete discussion of all principles of operation or applications, and is not to be construed as a limitation on the scope of the claimed subject matter.

KEY VISE STRUCTURE

BACKGROUND OF THE INVENTION

Key making machines in the past have been generally of the type wherein a relatively experienced operator operates the machine and gets used to the idiosyncrasies of such machine. In industrialized countries today the key duplicating machines are often found in retail merchandising stores of the type wherein many different people may operate the key making machine. Accordingly, many of the prior art machines were much too complicated for the ordinary retail store clerk to operate without considerable experience.

Accordingly, it is an object of the invention to provide a key-making machine with a vise structure which is simple and reliable to operate.

Another object of the invention is to provide a key vise structure wherein a single beam spring actuates two different key vises.

Another object of the invention is to provide a toggle mechanism to deflect a central portion of a beam spring, the ends of which actuate closed jaws of first and second vises for keys.

Another object of the invention is to provide a key vise structure wherein a key shoulder gauge is automatically retracted in a positive manner as the keys are clamped in the vises.

SUMMARY OF THE INVENTION

The invention may be incorporated in a key vise structure, comprising in combination, a frame having two ends, first and second vises mounted on opposite ends of said frame, each of said vises including movable vise jaw means and a secondary jaw, means movably mounting said movable vise jaw means on opposite ends of said frame for cooperation with the respective secondary jaws to hold a master key and a key blank at opposite ends of said frame, a beam spring mounted in said frame and extending from one jaw means to the other, mechanical advantage means mounted in said frame and acting on the central portion of said beam spring, and means to apply a force relative to said frame through said mechanical advantage means to stress said beam spring and move the ends thereof toward said movable jaw means to move said movable jaw means toward the respective secondary jaws to clamp the keys in the respective vises.

Other objects and a fuller understanding of the invention may be had by referring to the following description and claims, taken in conjunction with the accompanying drawing.

BRIEF DESCRIPTION OF THE DRAWINGS

FIG. 1 is a side elevational view of a key machine embodying the invention;

FIG. 2 is a top view of the machine of FIG. 1;

FIG. 3 is a front view of the machine with a part of the vise broken away showing the shoulder gauge;

FIG. 4 is an enlarged sectional view on line 4-4 of FIG. 2;

FIG. 5 is a partial sectional view on line 5-5 of FIG. 3; and,

FIGS. 6 and 7 are enlarged partial views of the vise toggle clamping mechanism in the clamped and released positions, respectively.

DESCRIPTION OF THE PREFERRED EMBODIMENT

The drawing illustrates a key machine 11 showing the construction of the preferred embodiment of the invention. This key machine has a main frame 12 pivotally supporting a cutter head 13 at a pivot 14. As shown in FIG. 5, a motor 15 on head 13 drives a milling cutter 16 through gearing 17 at a reduced speed and directly drives a brush 18 to aid in removal of any burr on the completed key.

The key machine 11 also includes a vise structure 20 including a first vise 21 and a second vise 22. These vises 21 and 22 are identical except for being mirror images of each other. The vise structure 20 includes a vise frame 23 which is mounted by a ball track 24 for longitudinally reciprocating movements on the main frame 12 toward and away from the milling cutter 16. A motor and speed reduction unit 25 is mounted in the main frame 12 and connected by a link 26 to the vise frame 23 to provide this powered longitudinal movement of the vise structure 20.

The two vises 21 and 22 each are adapted to mount a key. The first vise 21 in this preferred embodiment is adapted to mount a master key 31 which already has the proper bits or notches thereon and the second vise 22 is adapted to mount a key blank 32. The master key 31 is adapted to cooperate with a stylus 33 secured on the cutter head 13 to raise and lower the head 13 in accordance with the notches on the master key 31 so that the milling cutter 16 will cut corresponding notches on the key blank 32. A protective cover 34 for the cutter 16 and part of the brush 18 is shown in FIGS. 2 and 3 but shown removed in FIGS. 1 and 5.

FIG. 4 generally shows the internal construction of the vise structure 20 and since the first and second vises 21 and 22 are mirror images of each other, generally only the first vise 21 will be described. The first vise 21 includes movable vise jaw means 36 and a secondary jaw 39. The movable vise jaw means 36 includes a clamping block 37 and a separate jaw 38. The movable vise jaw means 36 is movably mounted on the frame 23 and in this preferred embodiment the block 37 is pivoted to frame 23 at the pivot 40. The secondary jaw 39 may be unitary with the vise frame 23 but in this preferred embodiment is a separate piece of hardened steel. Also the separate jaw 38 is a piece of hardened steel and these two jaws 38 and 39 are mounted by means of pins 41 to the vise frame 23 and this provides for limited movement between the two jaws.

A beam spring 43 lies inside the vise structure 20 and extends from the first vise to the second vise. The ends of the beam spring 43 cooperate with the clamping blocks in two ways. A coil compression spring 44 is disposed in a pocket 45 in the clamping block 37 and acts on the end of the beam spring 43. Also the clamping block 37 has a flat bearing surface 46 engaged by the end of the beam spring 43 upon slight compression of the compression spring 44. Mechanical advantage means 48 is mounted in the vise frame 23 and acts between the frame 23 and the central portion 49 of the beam spring 43. This mechanical advantage means includes a toggle mechanism 50 and a manual handle 51. The manual handle 51 may be considered a means to apply a force on the central portion of the beam spring 43 through the toggle mechanism 50. The handle 51 has clamped and released positions shown in FIGS. 6

and 7, respectively. The clamped position of the handle 51 closes the vise jaws and the released position of the handle 51 opens the vise jaws. The handle 51 has a fork at one end pivoted at a close fitting hole on a pivot pin 53 and has an L-shaped extension 54. The pivot pin 53 is carried in the vise frame 23. Slide plates 55 slide in the frame 23 and are guided for vertical movement by a slot 56 therein which receives a guide 57 fixed on the frame 23. These slide plates 55 have an elongated slot 58 encompassing the pivot pin 53 to provide this vertical movement. A pivot pin 59 is carried in the slide plates 55 to move vertically therewith. Toggle links 60 are pivoted on the pin 59 and on a knee pivot pin 61, which is closely received in a hole in the handle 51. When the handle 51 is in the released position shown in FIG. 7, then the beam spring 43 is substantially unstressed. When the handle 51 is moved to the clamped position of FIG. 6, then the handle extension 54 engages the pivot pin 59 to provide a limit position and to make sure that the knee 61 of the toggle is fully straightened to apply the maximum mechanical advantage in movement of the handle to the beam spring 43. A bearing plate 62 is mounted on the pivot pin 59 and is U-shaped to embrace and act on the central portion 49 of the beam spring 43 as the knee 61 of the toggle is straightened.

The vise structure 20 also includes a bottom gauge which includes a bottom gauge plate 64 mounted on the pins 41. This gauge plate may be moved into three different lateral positions by means of a cam follower 65 and a cam 66 moved by a handle 67. The handle 67 may be moved to the proper position for gauging single sided, double sided or foreign car keys and this will set the proper vertically gauged positions of the keys 31 and 32 relative to the vise structure 20.

As better shown in FIG. 2 the jaws 38 and 39 have outwardly bent lips 68 and 69 to aid in the longitudinal insertion of a key into the jaws.

The vise structure 20 also includes a shoulder gauge 70 as shown in FIGS. 1, 2 and 3. The shoulder gauge 70 is shown as a lever pivoted at 71 on the vise frame 23. This shoulder gauge lever 70 has gauging and retracted positions shown in the right and left halves of FIG. 3, respectively. Normally, both shoulder gauges are in the same position either the gauging or the retracted positions and FIG. 3 may be considered split along a vertical center line in order to show the parts in the different positions for the retracted and gauging positions. Both shoulder gauges for the two vises 21 and 22 are substantially identical, merely being mirror images of each other; hence, generally the only one of the shoulder gauges for a vise 21 will be described. The shoulder gauge 70 is adapted to engage a shoulder 72 on the key, as shown in FIG. 1, in order to establish the proper longitudinal position of the key relative to the vise structure 20.

The shoulder gauge lever 70 has a pin 73 engaging one end of a coil extension toggle spring 74. The other end of the spring 74 is mounted to an anchor 75 on the frame 23 in a position such that the axis of the spring lies on opposite sides of the lever pivot 71 for each of the gauging and retracted positions. This means that the line along which the force of the spring acts is on opposite sides of the pivot 71 for each of these two positions, and accordingly spring 74 acts as a toggle spring yieldably urging the lever 70 into each of these two positions. A retract lever 77 is pivoted on the vise frame

23. A ledge 78 is provided on the shoulder gauge 70 in a position to be acted on by the retract lever 77. The retract lever 77 has an extension 79 engaging a notch 80 in the slide plates 55. FIG. 3 shows the right hand slide plate 55 in the lower position in which it would be with the handle 51 in the released position. When the handle 51 is moved downwardly to the clamped position, this raises the slide plate 55 as shown by the left hand plate in FIG. 3 which acts on the retract lever 77 in turn acting on the ledge 78 to move positively the shoulder gauge 70 from the gauging to the retracted position. A cover 81, shown in FIGS. 1 and 2, is shown removed in FIG. 3 to reveal the shoulder gauges 70.

OPERATION

The key machine 11 may be operated by relatively unskilled personnel and in fact personnel who are relatively unpracticed in that particular machine. The manual handle 51 is normally in the released position shown in FIG. 7. In this condition the beam spring 43 is not stressed and the flat bearing surface 46 on the clamping blocks 37 is normally not touching the beam spring 43. The coil compression spring 44 provides a slight amount of resilient urging between the jaws 38 and 39. This permits a person to insert a master key, namely a key which he wishes to copy, between the jaws 38, 39. This readily may be accomplished by longitudinally inserting the key between the outwardly bent lips 68 and 69 to spread apart the jaws 38 and 39. The light force of the spring 44 easily retains the key in the desired position. FIG. 3 shows the two alternative positions for the shoulder gauge 70. With handle 51 raised, slide plate 55 is lowered and retract lever 77 is raised, as on the right half of FIG. 3, but gauge lever 70 remains in the retracted position shown on the left of FIG. 3. Next, the operator moves the shoulder gauge lever 70 from the retracted position shown on the left side of FIG. 3 to the gauging position shown on the right side of FIG. 3. With this lever 70 in the gauging position, the master key 31 is pushed longitudinally in until its shoulder 72 engages this shoulder gauge lever 70. This will be as shown in FIG. 1. In similar manner the key blank 32 is inserted and put in proper gauge position in the key vise 22.

With the keys 31 and 32 properly positioned, the handle 51 may be moved downwardly from the released position of FIG. 7 to the clamped position of FIGS. 1 and 6. As the handle is so moved, the toggle mechanism 50 straightens the knee 61 thereof to separate the pivot pins 53 and 59. This acts through the bearing plate 62 and forces the central portion 49 of the beam spring 43 upwardly. The ends of the beam spring 43 are consequently stressed upwardly. The light springs 44 are quickly compressed at the beginning of this movement and the ends of the beam spring 43 bear against the flat bearing surfaces 46 for positive movement of the clamping blocks 37. The nose of the clamping block 37 acts against the separate jaw 38 to move it toward the secondary jaw 39 and clamp the key 31 therebetween. In a similar manner the key blank 32 is also clamped in the second vise 22. Considerable force can be exerted on the keys especially the blank key 32 by the milling cutter 16. The present vise structure 20 provides positive clamping of both keys 31 and 32 by the simple downward movement of the handle 51. The mechanical advantage means shown as a toggle mechanism gives a very large mechanical advantage to exert

a very large clamping force on the keys and hence hold them stationary despite external forces on the keys.

As the handle 51 is brought downwardly to the clamped position, the slide plates 55 move upwardly to the position shown in the left half of FIG. 3. This upward movement moves the retract lever 77 downwardly engaging the ledge 78 and moving the shoulder gauge levers 70 positively inwardly to the retracted position. The first portion of this movement is resisted by the extension of the spring 74 but after the intermediate position of the lever 70, this spring 74 snaps the shoulder gauge 70 to the retracted position. This retraction mechanism is performed automatically as the handle 51 is moved to the clamped position and hence this makes sure that the shoulder gauges are not inadvertently left in position during the key cutting operation. Also this retract mechanism is a positive linkage, not something with a yielding spring action, and thus even though the shoulder gauge lever 70 frictionally drags on the shoulder 72, such lever is positively moved out of the way. Next, the motors 15 and 25 may be energized to drive the cutter 16 and to drive the vise structure 20 forwardly and rearwardly. The stylus 33 will follow the master key 31 to control the up and down movements of the cutter 16 and hence the notches will be cut on the key blank 32 in accordance with the notches on the master key 31. At the completion of the cutting movement it is a simple matter for the machine operator to move the handle 51 upwardly from the clamped to the released position to open the vises 21 and 22. The springs 44 still cause the jaws 38, 39 to lightly grip the keys, so they do not fall out, yet they may be easily removed by the operator. The brush 18 may be used to remove any burr remaining on the key after having been cut.

The present disclosure includes that contained in the appended claims, as well as that of the foregoing description. Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A key vise structure, comprising in combination, a frame having two ends, first and second vises mounted on opposite ends of said frame, each of said vises including movable vise jaw means and a secondary jaw, means movably mounting said movable vise jaw means on opposite ends of said frame for cooperation with the respective secondary jaws to hold a master key and a key blank at opposite ends of said frame, a beam spring mounted in said frame and extending from one jaw means to the other, mechanical advantage means mounted in said frame and acting on the central portion of said beam spring, and means to apply a force relative to said frame through said mechanical advantage means to stress said beam spring and move the ends thereof toward

said movable jaw means to move said movable jaw means toward the respective secondary jaws to clamp the keys in the respective vises.

2. A key vise structure as set forth in claim 1, wherein each of said movable vise jaw means includes a separate vise jaw and a clamping block, the key being clampable between the separate vise jaw and the respective secondary jaw.

3. A key vise structure as set forth in claim 2, wherein each clamping block is pivotally secured to an end of the frame and bears against an outer surface of said separate jaw.

4. A key vise structure as set forth in claim 1, including auxiliary spring means acting on each of said vises to lightly and temporarily hold in place a master key and a key blank between the movable vise jaw means and the secondary jaw, and being easily spread apart manually for insertion of the master key or key blank.

5. A key vise structure as set forth in claim 4, wherein said auxiliary spring means includes spring means acting between an end of said beam spring and one of said movable vise jaw means.

6. A key vise structure as set forth in claim 4, wherein said auxiliary spring means includes an auxiliary spring acting between each end of said beam spring and the respective movable vise jaw means.

7. A key vise structure as set forth in claim 1, including pockets in the lower surface of each said movable vise jaw means,

35 a coil compression spring disposed in each pocket and acting between the respective movable jaw means and an end of said beam spring to lightly and temporarily hold in place a master key and a key blank between the movable jaw means and the respective secondary jaw for initial positioning.

8. A key vise structure set forth in claim 7, including a flat bearing surface on each of said movable jaw means cooperable with the ends of said beam spring upon slight compression of said coil compression springs to establish positive movement of said movable jaw means by said beam spring.

9. A key vise structure as set forth in claim 1, including a toggle mechanism in said mechanical advantage means.

10. A key vise structure as set forth in claim 9, including a manual handle in said mechanical advantage means with said handle movably mounted in said frame and having clamped and released positions.

11. A key vise structure as set forth in claim 10, including a knee in said toggle mechanism movable over center by said handle when the handle is moved to said clamped position to lock the vises closed until the vises are physically released by moving the handle from the clamped position to the released position.

12. A key vise structure, comprising in combination, a frame, a vise mounted on said frame, force application means movable between clamped and released positions to actuate said vise between closed and opened positions, a key shoulder gauge for said vise including a lever pivoted on said frame adjacent said vise and having gauging and retracted positions, overcenter spring means acting between said lever and said frame whereat the force of said spring

means yieldably restrains said shoulder gauge in each of said gauging and retracted positions, said spring means being a coil extension spring connected to said lever and to said frame in a manner such that the axis of said spring is alternatively on one side and the opposite side of said shoulder gauge lever pivot in said gauging and retract positions, respectively.

13. A key vise structure as set forth in claim 12, wherein said linkage means includes a retract lever, a ledge on said shoulder gauge engageable by said retract lever, and means pivoting said retract lever on said frame in a position to engage said shoulder gauge ledge to move same and retract said shoulder gauge as the force application means is moved from said released to said clamped position.

14. A key vise structure as set forth in claim 12, including only positive mechanical connections in said

linkage means to assure positive rather than yielding movement of said shoulder gauge as said force application means is moved from said released to said clamped position.

5 15. A key vise structure as set forth in claim 12, wherein said spring means is a single spring acting as a toggle spring.

10 16. A key vise structure as set forth in claim 12, including in said force application means a manual handle movably mounted on said frame, and a toggle clamp moved by said manual handle to actuate said vise.

15 17. A key vise structure as set forth in claim 16, wherein said linkage means is connected to said toggle clamp to move said shoulder gauge lever to the retracted position as the knee of said toggle clamp is straightened.
